John H. Gage

INVENTOR

Edward E. Gage

UNITED STATES PATENT OFFICE.

EDWARD E. GAGE, OF NEW YORK, N. Y.

LOCK.

1,249,738.

Specification of Letters Patent. Patented Dec. 11, 1917.

Application filed March 7, 1917. Serial No. 153,185.

To all whom it may concern:

Be it known that I, EDWARD E. GAGE, a citizen of the United States, and a resident of New York, borough of Manhattan, in the county of New York and State of New York, have invented certain new and useful Improvements in Locks, of which the following is a full, concise, and exact description, such as will enable others skilled in the art

10 to practice my invention.

My invention relates to locks and more particularly to door locks and the main object of my invention is to produce a lock of few and simple parts which may be interchangeably used as a safety lock operable from either side of the door or a dead lock which can be operated only from the outside of the door by a properly constructed key.

In accordance with the general features 20 of my invention there is provided mechanism located within the casing of the lock and accessible only in the unlocked position of the bolt, which may be operated by the user to make the lock a dead lock whereby it 26 is operable only by the proper key and from the outside of the door or it may be made an ordinary safety lock operable by hand from the inside of the door or by key from the outside of the door. More specifically, my 30 invention comprises a pair of adjustable pins or plungers carried by a member operable by the key mechanism and adapted in their operated positions to engage the locking bolt under different conditions to move it into 35 and out of engagement with its coöperating socket. One of said pins when in operative position to the bolt remaining in engagement therewith when said bolt is in its locked position to prevent the movement 40 thereof except by act of turning the key in the lock, the other of said pins being adapted to engage said bolt in the operation of moving it by means of the key and to be disengaged therefrom when said bolt is in 45 either of its extreme positions to which it must be moved in order to permit the removal of the key from the lock.

As a further feature of this invention, means are provided whereby the lock when 50 it is set as a dead lock and operated by the key it will automatically be reset to a safety position and can be set again as a dead lock only by hand and from the inside of the door. For this purpose means are provided 55 for engaging the dead lock pin when the bolt is moved to the extreme of its unlocked

position to render said dead lock pin inoperative and the safety lock pin operative.

In the drawings illustrating this invention

Figure 1. is a fragmentary view of the inside of a door and door casing illustrating a lock embodying the features of my invention applied thereto;

Fig. 2 is a view of the inside of my lock illustrating the parts in the locked position;

Fig. 3 is a view similar to Fig. 2 with the parts in the unlocked position;

Fig. 4 is a detail sectional view taken upon line 4-4 of Fig. 3;

Fig. 5 is a detail sectional view of the 70 parts taken upon line 5-5 of Fig. 2;

Fig. 6 is a detail view of the safety and dead lock mechanism, and

Fig. 7 is a detail sectional view taken upon line 7-7 of Fig. 6.

In the drawings, 5 designates a casing within which is located a locking bolt or securing means 6 adapted to register with a socket 7 in the door casing. The bolt 6 is provided on its inner end with a projecting 80 portion 8 which has formed in one face thereof an elongated recess 9, the other face being flat and adapted to bear against the inner face of the casing 5 which serves as a guide for one side of said bolt 6 the opposite 85 side of which is provided with a flange 10 working in a guideway 11 of an attaching plate 12 by means of which the inner part of the lock is secured to the door. A second projection 13 on the bolt 6 located near the 90 center thereof is provided with a sloping faced cam surface 14. Located within the casing 5 is a cylindrical member 15 having a flattened portion 16 upon which is mounted a centrally pivoted lever 17 to the opposite ends of which are secured pins or plungers 18 and 19. These pins or plungers 18 and 19 project through the end of the cylindrical member 15 for the purpose herein- 95 after set forth.

The cylindrical member 15 is secured by means of a shank 20 to a key barrel or guide 21 rotatably mounted in a cylinder 22 carrying spring pressed tumblers or plungers 23, 23 projecting into said barrel 21 and adapted to coöperate with a key 25 in a well known manner. The lock is of that class in which the key can be inserted into or withdrawn from the lock only in one position of the barrel or guide 21. An opening 26 in the casing 5 renders the pins or plungers 18 and 19 normally accessible when the bolt 6 is in 110

its unlocked position but is covered by the projecting portion 8 when the bolt is in its locked position.

The pins or plungers 18 and 19 are reciprocal in their action, that is pressure upon the plunger 18 to move it inwardly will cause the plunger 19 to move outwardly and pressure upon the plunger 19 to move it inwardly will move the plunger 18 outwardly.

In order to make the lock a dead lock or one which can be operated only by a key from the outside of the door, it will be necessary to push the pin 18 inwardly thus causing the pin 19 to move outwardly with the major portion thereof projecting beyond the end of the cylindrical member 15. Assuming that the bolt 6 is in its unlocked position as shown in Figs. 1 and 3, the projecting portion 8 will be in a position to uncover the opening 26 thus exposing the pins 18 and 19 to one inside the door. In the operation the key will first be inserted and the lock turned through a slight angle sufficient to bring the end of the pin 19 above the upper edge of the bolt 6 where it will be free to move outwardly when pressure is exerted upon the pin 18 which may be done by the finger or a pencil or like means which will enter the opening 26. When the pin 19 is moved outwardly in this manner the pin 18 will be in and its end will clear the bolt 6 upon the turning of the cylindrical member 15. Now upon the continued rotation of the key 25 the projecting end of the pin 19 will engage in the elongated recess 9 in the projecting portion 8 and will by reason of this engagement move the bolt 6 into engagement with the socket 7 in the door casing. A complete rotation of the key 25 will bring it into a position where it may be removed from the barrel 21. This movement, however, will have brought the pin 19 back to the same angular position in which it was when the key was first inserted into the lock but instead of being adjacent the cam surface 14 it will be in the recess 9 and the bolt 6 will be in its extended position with the projection 8 fully covering the opening 26 in the casing 5 thereby preventing manipulation of the pins 18 and 19. The pin 19 now being in engagement with the recess 9 operation of the bolt 6 is impossible without turning the barrel or key guide 21 and this is possible only by the removal of the tumblers or plungers 23, 23 from the barrel 21 which can only be accomplished by means of the proper key. The opening 26 now being covered by the projecting portion 8 of the bolt 6, operation of the bolt from the inside of the door is wholly impossible without removing the casing 5 since the cylindrical member will have to be freed from the bolt 6 which can only be done by reversing the positions of the pins 18 and 19. In unlocking the door by

means of the key 25 it will after insertion be turned in a direction opposite to that in which it was turned to lock the door whereupon the pin 19 by reason of its engagement with the recess 9 will move the bolt 6 backwardly and a complete revolution of the cylindrical member 15 will move the pin 19 from engagement with the recess 9 and cause the projecting end of said pin 19 to engage the sloping cam face 14 of the projection 13 on the bolt 6 to push said pin 19 inwardly then throwing the pin 18 outwardly. In this position of the parts the bolt 6 is entirely free of the cylindrical member 15 and may be moved backwardly and forwardly by one on the inside through the agency of a knob 30 or by operation of the key from the outside the pin 18 may be caused to engage the recess 9 to move the bolt 6 in either direction. Due, however, to the fact that the key has to be moved through a complete revolution in order to remove it the pin 19 cannot be left in any position except one in which it is out of engagement with the bolt 6. The pin 19 now being in its inward position it cannot engage any portion of the bolt 6.

It will be obvious from the above description that by manipulation of either the pin 18 or 19 the lock may be made a safety lock operable by hand from the inside or a dead lock operable only by the key from the outside of the door.

While the bolt 6 is shown and described as being operable manually from the inside or by a key from the outside, it is quite obvious that it might be moved into engagement with the socket 7 in the door casing by means of a spring.

Having now described my invention, which may vary in detail without departing from the spirit thereof, what I claim, and desire to secure by Letters Patent, is—

1. In a lock, a securing member, a rotatable member, a key for operating said rotatable member, and adjustable means carried by said rotatable member, said adjustable means being adapted in one position to render said securing member operable only by the key from one side of the door and in another position to render said securing member operable by key from one side of the door and by hand from the other side of the door.

2. In a lock, a socket, a securing member slidable into and out of engagement with said socket, a casing in which said securing member is housed said casing being provided with an opening therethrough, a rotatable member in said casing movable only by a key, an adjustable locking pin adapted in one position to lock said rotatable member and said bolt together and accessible through said opening only when said securing means is in unlocked position and means

controlled by said securing member in its locked position for covering the opening in said casing.

3. In a lock, a casing, a securing member located in said casing a rotatable member in said casing movable only by a key, a pair of reciprocally operating pins carried by said rotating member and adapted to be alternately brought into operative relation with respect to said securing member, a projecting member on said securing member provided with a recess therein adapted to be engaged by either of said pins, one of said pins being adapted to engage said recess in the locked position of said securing member and the other of said pins when in operative position being adapted to engage said recess only in the operation of said rotatable member by said key.
4. In a lock, a securing member, a rotatable key operated member, and adjustable means carried by said rotatable key operated member for rendering said securing means operable by a key only or for rendering it operable by key or hand at will.
5. In a lock, a securing member, a key operated member, and a pair of reciprocally operating pins carried by said key operated member and operable by hand when said securing member is in unlocked position, one of said pins being adapted in its operated position to engage said securing member to make said lock a dead lock operable only by a key, the other of said pins being adapted when in operated position to render said securing means operable by key or by hand.
6. In a lock, a securing member, a casing in which said securing member is housed said casing having an opening therethrough, a key operated member located within said casing and a pair of reciprocally operated pins carried by said key operated member and accessible for operation through the opening in said casing one of said pins serving to render said securing member operable only by a key, the other of said pins rendering said securing member operable by hand or by key at will.
7. In a lock, a securing member, a key operated member, adjustable means operable by hand to render said securing member operable by key only and means operating upon the operation of said securing means by said key for rendering said securing means operable by hand.
8. In a lock, a securing member, a key operated member, a dead lock pin carried by said key operated member and adapted to be moved by hand to engage said securing member to render said securing member operable only by a key and means operative upon a complete rotation of said key operated means to render said dead lock pin ineffective.
9. In a lock, a securing member, a key operated member, a pair of reciprocally operating pins carried by said key operated member and adapted to coöperate with said securing member to make said lock a dead lock or a safety lock, and means effective upon a complete rotation of said key operated member for rendering said dead lock pin ineffective and said safety lock pin effective.
10. In a lock, a securing member, adjustable means adapted in one position to render said securing member operable only from the outside of the door by a key and in its other position to render said securing member operable from the outside of the door by a key or by hand from the inside of the door, and means for rendering said adjustable means inoperative by hand from the inside of the door when in position to render said securing member operable by key only from the outside of the door.
11. In a lock, a securing member, adjustable means adapted in one position to render said securing member operable only from the outside of the door by a key and in its other position to render said securing member operable from the outside of the door by key and from the inside of the door by hand, and means controlled by said securing member for rendering said adjustable means wholly inoperative from the inside of the door when said adjustable means is in position to render said securing member operable only by key from the outside of the door.

In witness whereof, I hereunto subscribe my name this sixth day of March, A. D. 1917.

EDWARD E. GAGE.
